[57] CLAIM

The ornamental design for a toilet training unit for a child, as shown and described.

DESCRIPTION

FIG. 1 is a top perspective view of a toilet training unit for a child showing our new design;

FIG. 2 is a front elevational view thereof;

FIG. 3 is a left side elevational view thereof, the right side being a mirror image of the left side;

FIG. 4 is a rear elevational view thereof;

FIG. 5 is a top plan view thereof; and,

FIG. 6 is a bottom plan view thereof.
